(57) CLAIM

The ornamental design for a chair joint, as shown and described.

DESCRIPTION

FIG. 1 is a perspective view of a chair joint showing my new design;

FIG. 2 is a front elevational view of the chair joint of FIG. 1;

FIG. 3 is a rear elevational view of the chair joint of FIG. 1; FIG. 4 is a left side elevational view of the chair joint of FIG. 1;

FIG. 5 is a right side elevational view of the chair joint of FIG. 1;
